(57) **CLAIM**

We claim an ornamental design for a light emitting diode, as shown and described.

DESCRIPTION

FIG. 1 is a perspective view of the light emitting diode, showing our new design;

FIG. 2 is a front elevation view of the light emitting diode of FIG. 1;

FIG. 3 is a rear elevation view of the light emitting diode of FIG. 1 wherein the broken lines define portions of the light emitting diode that forms no part of the claimed design;

FIG. 4 is a left side elevation view of the light emitting diode of FIG. 1;

FIG. 5 is a right side elevation view of the light emitting diode of FIG. 1;

FIG. 6 is a top plan view of the light emitting diode of FIG. 1; and,

FIG. 7 is a bottom plan view of the light emitting diode of FIG. 1.
